UNITED STATES PATENT OFFICE.

JAMES P. SWIFT AND JAMES H. SWIFT, OF EVANSVILLE, INDIANA.

DOOR-CHECK.

SPECIFICATION forming part of Letters Patent No. 374,563, dated December 6, 1887.

Application filed June 25, 1887. Serial No. 242,487. (No model.)

To all whom it may concern:

Be it known that we, JAMES P. SWIFT and JAMES H. SWIFT, both of Evansville, in the county of Vanderburg and State of Indiana, 5 have invented certain new and useful Improvements in Combined Door-Checks and Alarms, of which the following is a full, clear, and exact description.

Our invention relates to improvements in 10 the class of devices an example of which is given in the patent to James H. Swift, dated June 20, 1876, No. 178,976.

The object of our invention is to provide for 15 the ready adjustment of the curved locking-bar shown in said patent for variously-hinged doors, and to furnish a simple and convenient latch for working the check-bolt, together with an arrangement for operating said latch, locking the door, and sounding an alarm by the 20 turning of the door-knob.

We will first describe a device of this character embodying our invention, and then point out the nature of the improvements in claims.

Reference is to be had to the accompanying 25 drawings, forming a part of this specification, in which similar letters of reference indicate corresponding parts in all the figures.

Figure 1 is a view of door, showing a device 30 embodying our improvements applied thereto, the knob-spindle being in section. Fig. 2 is an enlarged sectional plan of the curved locking-bar when rendered adjustable by our improvement. Fig. 3 is a front elevation of the 35 said locking-bar. Fig. 4 is a perspective view of a check-bolt-operating latch and its tripping device in which our improvements are embodied.

A designates a door; B, a spring check-bolt; C, its case secured to the top of the door and 40 having a guide-slot for the curved locking-bar D, with holes in which the bolt B engages; E, an angle-lever for retracting the spring-bolt B; F, a bell-crank lever connected with the angle-lever E by a cord or wire, G; H, a wire for 45 drawing on the bell-crank lever F and retracting the bolt, all as described in the before-mentioned patent to J. H. Swift.

The hinges of different doors may set out at 50 various distances from the door-frame, and in order that the hinge-pins may always be aligned with the center of the curve of the locking-bar D, we continue the free ends of the

same to form straight parallel extensions D', which are adjustable lengthwise in fixed sockets I in the door-frame.

55

We prefer to construct the sockets I by forming mortises I' in the door-frame and securing over the mouths thereof plates J, each having a slot, J', to receive closely the corresponding locking-bar extension D' and lugs J², formed 60 with perforations, through which and one of a series of holes D² in said extension pins or bolts J³ are passed to hold the bar D firmly in position. The lugs on the plate J over the doorway are passed into the mortise I', to allow 65 the door to close fully; but the lugs on the other plate J may project on the outside, as shown, as the frame-molding will prevent the door from swinging back to the wall. With this adjustability of the locking-bar it may 70 easily be so set that the bolt-case on the door will not bind the bar in swinging.

For drawing down upon the cord or wire H, and thus retracting the bolt, we employ a latch of a description clearly illustrated in Fig. 4. 75 This consists of a locking-plate, K, secured to the door A adjacent to the knob and a spring-arm, L, pivoted to the plate K, having a handle, L', and on its inner side a pin or stud, L², adapted for insertion in one of a segmental series of holes, K', in the plate K, so that on drawing down the arm L to retract the check-bolt it can readily be locked in such position, or as readily unlocked to allow the spring 80 check-bolt to engage the locking-bar D. As a 85 simple and convenient device for unlocking or tripping said latch by turning the door-knob, we provide an elastic metal angle-bar, M, having a squared slot, M', in its lower end to fit over the squared spindle of the knob, and pivoted to its upper end a toothed segment, N, provided with a central upwardly-projecting pin, O.

The segment N is adapted to rock transversely on the face of the door, its teeth preventing it from slipping thereon, so that the latch-arm L, being drawn down in front of the pin O on the rocking segment, on turning the knob in either direction the bar M will rock the segment, moving the pin O outward and 95 withdrawing the pin or stud L² on the latch-arm from the locking-plate. As the spring check-bolt B is thus released, it engages the locking-bar D and securely locks the door. 100

Having thus described our invention, what we claim as new and desire to secure by Letters Patent, is—

1. In a door-check of the character described, the combination, with a door-frame having fixed sockets I, of a curved locking-bar, D, having parallel end extensions, D', adjustable lengthwise in said sockets, and means for holding the bar D in its adjustment, substantially as shown and described.
2. In a door-check of the character described, the combination of fixed plates J, provided with slots J' and perforated lugs J'', a curved locking-bar, D, having perforated ends received in the slots J', and pins passed through the perforations in the lugs J'' and in the ends of the bar D, substantially as shown and described.
3. In a door-check, the combination of the

spring-bolt B, the cord or wire H, for operating the same, the handled pivotal spring-arm L, connected to said cord or wire and having a stud, L², and the locking-plate K, having a circular series of holes, K', adapted to receive the stud L², substantially as shown and described.

4. The combination of the laterally-unlocking latch-arm L, the rocking segment N, the pin O on the same arranged to engage the latch-arm L, the swinging bar M, for rocking the segment, and the knob-spindle for operating the bar M, substantially as shown and described.
